UNITED STATES PATENT OFFICE.

EMIL S. LEMME, OF SAN FRANCISCO, CALIFORNIA.

INTERLOCKING BUILDING-BLOCK.

1,282,090.

Specification of Letters Patent. Patented Oct. 22, 1918.

Application filed March 20, 1917. Serial No. 155,967.

To all whom it may concern:

Be it known that I, EMIL S. LEMME, a citizen of the United States, residing at the city and county of San Francisco and State 5 of California, have invented new and useful Improvements in Interlocking Building-Blocks, of which the following is a specification.

My invention relates to the construction 10 of building blocks or bricks of that class which is formed of plastic material molded in the desired shape and made hollow, with connecting interior passages for ventilation.

It consists in the molding of hollow blocks 15 with transverse ribs, having segmental horizontal channels adapted to register to form circular openings; and raised ribs and corresponding depressions are made upon the meeting faces and ends, to cause the blocks 20 to register properly and to gage and space them, for the proper amount of mortar in the joints. It also consists in forming the raised ribs of such less length than the blocks as to leave spaces through which electric 25 wires and other connections may be made without perforating or damaging the blocks.

Having reference to the accompanying drawings—

Figure 1 is a vertical section of the blocks 30 in a wall.

Fig. 2 is a perspective view of a block.

Fig. 3 is a vertical section on line 3—3 of Fig. 4.

Fig. 4 is a vertical section on line 4—4 of Fig. 3.

Fig. 5 is a detail section on line 5—5 of Fig. 4.

Fig. 6 is a detail plan view of the interlock of contiguous blocks.

Fig. 7 is a section of the end, showing the interlock.

Fig. 8 is a corner fragment.

Fig. 9 shows the corner construction.

The blocks or bricks A are made of any 45 suitable or conventional exterior form, with side and end walls of sufficient thickness for strength and forming vertical, rectangular interior passages a which, when the blocks are laid up to form a structure, will provide 50 a hollow wall with ample ventilating space and draft.

Midway between the ends, ribs 2 are formed, dividing the hollow space, and when the blocks are laid in courses to form a wall, 55 the ribs register with the ends of alternate

blocks, so that a series of vertical air spaces or channels a will be formed throughout the walls. In order to provide for transverse movement of the air through the walls, the ribs and end walls of each block have semi-circular channels 2^a formed at the top and bottom, and when the blocks are laid to form a structure, the registration of the ribs and end walls brings two of these semicircular channels together, so that horizontal 60 channels are formed intersecting the vertical channels, and providing for a complete circulation in all directions through the wall.

The blocks are rapidly and accurately laid and adjusted upon each other by forming 65 extension flanges 3, upon one surface at the inner edges of the hollow walls and corresponding inter-engaging depressions 4 upon the opposite surface. The ends of the blocks have projecting flanges 5, at one end, and 70 depressions 6 into which the flanges fit when the blocks are laid up, and are thus correctly matched together. (See Fig. 6).

In order to gage the interspacing of the 75 joints and the amount of mortar to be 80 spread upon the meeting surfaces, without undue loss of time and material, the projecting ribs or flanges 3 are higher than the depth of the corresponding depressions, so that when matched together, they contact 85 with the bottoms of the depressions and retain the edges of the blocks apart. (See Figs. 1, 2 and 3).

In order to form passages from the exterior to the interior channels to make electrical or other connections and conduits, the ends of the flanges or ribs 3 stop short of the ends of the blocks A, so that when laid a transverse space will be formed between adjacent flanges at the meeting ends, as at 3^a, 90 and at the crossing rib 2 of the block of the next succeeding course, and through these 95 passages connections may be made with conductors concealed within the walls. These spaces also admit the passage of air, increase 100 the circulation and maintain a warm and dry condition.

The blocks may be connected in a horizontal or vertical position without in any way 105 interrupting the air currents or connections, and thus architectural variations are provided for. Metal bars 7 may also be introduced in these channels or passages for securing nailing strips, joist anchors, reinforcing rods, etc.

It will be manifest that a structure built of blocks of this description will be thoroughly ventilated and capable of a reinforced connection with the remaining structure units of the building of which the blocks form a part for the metal anchors 8 can be passed through the slots or openings 3^a from the interior to the exterior and connect with structural joists or other attachments, as at 10 9, Fig. 1.

Having thus described my invention, what I claim and desire to secure by Letters Patent is—

1. A hollow interlocking building block 15 having longitudinal flanges on one side terminating short of the end walls and longitudinally spaced depressions in its opposite side of less depth than the flanges whereby the end walls of the block will be spaced 20 from relatively superposed blocks, and a transverse partition wall dividing the hollow interior of the block and extending at one end between the spaced depressions to 25 interlockingly engage with the spaced opposing ends of the flanges of a relatively

subjacent pair of abutting blocks to hold the same against longitudinal movement.

2. A hollow interlocking building block having longitudinal flanges on one side terminating short of the end walls and a depression in its opposite side of less depth than the flanges whereby the end walls of the block will be spaced from relatively superposed blocks, and a transverse partition wall dividing the interior of the block and 35 extending at one end above the end walls to lie flush with the longitudinal flanges whereby to extend across the longitudinally aligned spaces above the end walls to guard against the entrance of a conduit into such 40 longitudinally aligned spaces, said walls being provided with registering channels for receiving conduits.

In testimony whereof I have hereunto set my hand in the presence of two subscribing 45 witnesses.

EMIL S. LEMME.
